UNITED STATES PATENT OFFICE

141,262

DESIGN FOR A NIGHTGOWN

Jane Z. Wade, Duluth, Minn.

Application January 22, 1945, Serial No. 117,529

Term of patent 3½ years

(Cl. D3—17)

To all whom it may concern:

Be it known that I, Jane Z. Wade, a citizen of the United States, residing at Duluth, in the county of St. Louis and State of Minnesota, have invented a new, original, and ornamental Design for a Nightgown, of which the following is a specification, reference being had to the accompanying drawing, forming a part thereof.

Fig. 1 is a front elevational view of a nightgown, showing my new design, and

Fig. 2 is a back elevational view of said nightgown.

I claim:

The ornamental design for a nightgown, substantially as shown.

JANE Z. WADE.
